UNITED STATES PATENT OFFICE.

OLOF NELSON, OF DUBOIS, PENNSYLVANIA.

PICTURE-HANGER.

SPECIFICATION forming part of Letters Patent No. 642,997, dated February 6, 1900.

Application filed November 21, 1899. Serial No. 737,794. (No model.)

To all whom it may concern:

Be it known that I, OLOF NELSON, a citizen of the United States, residing at Dubois, in the county of Clearfield and State of Pennsylvania, have invented certain new and useful Improvements in Picture-Hangers; and I do hereby declare the following to be a full, clear, and exact description of the invention, such as will enable others skilled in the art to which it appertains to make and use the same.

This invention relates to means for suspending pictures and like decorative devices of house furnishings from walls and partitions, the object being to provide a device of novel construction which will admit of the inclination of the picture or analogous wall decoration being varied to suit the taste without having to let out or take up the picture-cord or to change the point of attachment of said cord therewith.

For a full description of the invention and the merits thereof and also to acquire a knowledge of the details of construction of the means for effecting the result reference is to be had to the following description and to the drawings hereto attached.

While the essential and characteristic features of the invention are necessarily susceptible of modification, still the preferred embodiment of the invention is illustrated in the accompanying drawings, in which—

Figure 1 is a perspective view of the hanger, picture-cord, and intermediate adjustable connection. Fig. 2 is an edge view showing the application of the hanger and an adjusted position of the picture by dotted lines. Fig. 3 is a detail view of the hook with its wings extended.

Corresponding and like parts are referred to in the following description and indicated in all the views of the drawings by the same reference characters.

The hanger is provided at its upper end with a suspending eye or loop 1 and at its lower end with offstanding supports 2, and in the preferred form of construction consists of a frame formed of stout wire bent into approximately the form shown. The frame comprises legs 3 and a shank 4, the lower ends of the legs being bent outwardly to form the off-standing supports 2 and having their upper ends inwardly convergent and terminating in

members comprising the shank 4. In constructing the hanger a wire of suitable length and gage is provided and is doubled upon itself at a middle point, forming the eye or loop 1 and the members of the shank 4, the end portions of the wire being spread to provide the legs 3, which have their terminals outwardly bent to form the supports 2. 55

A hook 5 or analogous device is located at the juncture of the legs 3 and shank members 4 and is provided at its upper end with wings 6, which are adapted to be bent around and embrace the ends of the shank members 65 adjacent to the legs 3 and prevent their spreading. This hook 5 has the chain 7 or analogous connection between the picture-cord 8 and the hanger adjustably connected therewith, the links of the chain forming convenient means for adjustable connection of the part 7 with the hook, whereby the relative inclination of the picture 9 or like device to be hung may be varied as required without necessitating the lengthening or shortening 75 of the picture-cord or the change of the point of attachment of said cord with the frame of the picture.

The offstanding supports 2 are preferably clothed to prevent injurious contact therewith of the picture-frame, and, as shown, short lengths of rubber tubing 10 are fitted thereon. The outer ends of the supports 2 are threaded to receive ornaments 11, which are detachably fitted thereto and give a finished appearance to the lower portion of the hanger, besides acting in the capacity of stops to prevent the slipping of the picture or ornamental hanging from the supports 2. 80

The picture 9 or analogous article to be suspended is provided with a cord 8, attached thereto in the usual manner by means of screw-eyes 12, and is adapted to be hung at any required inclination with reference to the wall by means of the hanger and the adjustable connection 7, the latter being attached at one end to the picture-cord 8 and having its opposite end portion adjustably connected with the hook 5 in the manner stated. By preference the adjustable connection 7 is a short length of chain, because advantage can be taken of the links as means of attachment of the said part 7 with the hook 5 in an adjusted position. The picture or like article 85 90 95 100

can be fitted to the hanger prior to placing the latter in its final position upon the wall, and after the adjustment has been effected the hanger can be placed in position by being suspended from a nail or like support driven into the wall at the proper point.

Having thus described the invention, what is claimed as new is—

1. Means for suspending pictures comprising a hanger-frame having offstanding supports at its lower end and a shank at its upper end surmounted by a suspending device, a hook fitted to the shank portion of the hanger-frame, and a connection having adjustable attachment with the said hook and adapted to be made fast to the picture to be hung, substantially as described.
- 15 2. The herein-described hanger constructed

of a single length of wire doubled upon itself and bent to provide a suspending eye or loop, contiguous shank members and divergent legs terminating at their lower ends in off-standing supports, a hook having side wings bent about the members of the shank to prevent their spreading, and a chain or analogous connection adjustably interposed between the suspending means of the picture or like article and the hook of the hanger, substantially as and for the purpose set forth.

In testimony whereof I affix my signature 30 in presence of two witnesses.

OLOF NELSON. [L. S.]
